Application August 11, 1944, Serial No. 548,962

12 Claims. (Cl. 179—2.5)

1

This invention pertains to carrier wave communications systems in general, and more particularly to a system for utilizing a frequency-modulated transmitter at a central station for signal distribution over relatively large areas by means of public utilities lines or other conductors, and receiving said signals in predetermined signal areas or zones on frequency-modulated zone receivers, and re-transmitting the signals at each particular localized signaling zone on an amplitude-modulated zone transmitter.

By utilizing the system of the present invention, the high level of noise interference ordinarily encountered on power lines and other conductors may be substantially eliminated because the frequency modulation employed at the central station has a greatly improved signal to noise ratio over that provided by an amplitude-modulated system.

My Patent No. 2,389,257, dated Nov. 10, 1945, for a Carrier wave signaling system, discloses in general a system utilizing power lines, wayside conductors, or any available conductors in general for establishing a distributing network so that a central station transmitter may be used in conjunction with repeater stations. The central station in the above-mentioned patent relies generally on utilizing a central transmitter operating on a comparatively low frequency while the repeater station receives the signalling impressed upon the distributing network and redistributes it in localized zones on a different frequency, such as on frequencies ordinarily incorporated in the broadcast spectrum.

The present invention, however, differs in general from that of said patent in that the present invention employs frequency modulation at the central station transmitter, the signals of said transmitter being received in localized signaling zones and re-transmitted on amplitude-modulated transmitters so that the conventional home type receivers may be employed for receiving signals which originated at the central station as frequency modulated signals.

Throughout the application the term "distributing network" or "wayside conductors" is understood to mean any or all types of conductors such as power lines, telephone or telegraph lines, cables, rails, pipe lines or any suitable conductor which permits adequate operation of the system.

It is an object of the present invention to provide a carrier wave communication system utilizing power lines, telephone lines, telegraph

2

lines, or any other suitable conductors for establishing communications coverage over a relatively large area, wherein a central station or master transmitter impresses frequency-modulated signals on power lines or other conductors. The frequency-modulated signals may be received in predetermined signaling zones or areas on frequency modulation types of receivers, the outputs of which are impressed upon local zone transmitters which in turn impress amplitude-modulated signals on localized conductors (which may or may not be part of the conductor system over which the frequency modulated signals are carried) for establishing local signaling zones or areas.

A further object of the invention is to provide a system of the class described wherein frequency-modulated signals are impressed upon public utility lines or other wayside conductors which embrace a relatively large area, and having said signals received on frequency-modulated zone receivers and retransmitted on amplitude-modulated zone transmitters in localized zones, with the frequency of adjacent amplitude-modulated zone transmitters being different from one another to restrict interzone interference.

A further object of the invention is to provide various means of coupling a central station or master transmitter to a distributing network embracing a relatively large area so that the amplitude-modulated transmitters of repeater stations may retransmit, over localized areas a signal which originally was transmitted from the central station on a frequency-modulated transmitter. By this means conventional amplitude-modulated broadcast receivers may be employed for receiving intelligence which originated at the central contact station as frequency-modulated signals.

A further object of the invention is to provide a repeater booster comprising a receiver and transmitter with a relay control system which is employed at a point on the power lines or other conductors where there is appreciable attenuation, said attenuation usually being caused by excessively long lines or caused when said conductors run for a considerable distance underground or through metal conduit.

Further and other objects may be and may become apparent from a perusal of the present disclosure, since the present showing is by way of illustration only and is not to be construed as a limitation except as defined by the supporting claims.

In the drawings:

Fig. 1 is an overall block diagram of an induction radio system.

Fig. 1A is a modification of Fig. 1, showing an alternative method of coupling the equipment to the distribution network.

Fig. 2 is a block diagram of a frequency-modulated transmitter.

Fig. 3 is a schematic diagram of a frequency-modulated transmitter as represented in block diagram Fig. 2.

Fig. 4 is a block diagram of a frequency modulation zone receiver having means for coupling to a zone transmitter.

Fig. 5 is a schematic diagram of the frequency modulated zone receiver shown in block diagram Fig. 4.

Fig. 6 is a block diagram of an amplitude modulated zone transmitter.

Fig. 7 shows the schematic diagram of the amplitude modulated transmitter shown in Fig. 6.

Referring to the drawings, and more particularly to Fig. 1 thereof, the numeral 8 designates a high voltage line, as for instance a 23,000 volt line, on which is a 100 kilocycle frequency modulated carrier and 23,000 volt feeders extending throughout the service zone.

A microphone 15 or dual turntable with suitable amplifiers 14 is connected to a 100 kilocycle frequency modulated central station transmitter 13. Said transmitter is coupled to the 115 volt line 12 and feeds through its associated transformer 11, 2300 volt line 10 and then through transformer 9 into the 23000 volt feeders 8 extending throughout the service area.

There are here shown zones 1 and 2, and as the description of one zone will suffice for both or any duplication thereof, the apparatus in zone 1 will be described.

The transformers 16 and 18 of zone 1 connected by lines 17 and 19 feed the 100 kilocycle FM carrier to the 100 kilocycle FM zone receiver 20. The output of zone receiver 20 is coupled to a 590 kilocycle amplitude modulated zone transmitter 22. This zone transmitter 22 is automatically controlled by a FM carrier operated relay circuit 23, which operates the transmitter 22 whenever the central station transmitter 13 is in operation. The output of said transmitter 22 is coupled back into the power lines 19, 17, and 26 through its associated transformers 18 and 25 into a standard broadcast receiver 27, any number of which similar receivers can be operated on various sub-circuits in the zone.

In Figs. 2 and 3, the central station transmitter is shown in greater detail. Frequency-modulation is employed in this transmitter and also in the zone receivers in order to minimize disturbances, due to noise.

As will be seen in the block diagram Fig. 2, a microphone 27, which may be any type of signal originator, is connected to a reactance tube modulator 28, which is coupled to an oscillator 29, and a power amplifier 30, attached to an antenna 31.

In Fig. 3, this apparatus is set forth in greater detail and may be taken as indicative of one form that this may assume. In this figure oscillator tube 34 is coupled through variable resistor 82 and capacitor 42 supplying radio frequency energy to the reactance modulator tubes 32 and 33 and their associated circuit which functions in a conventional manner when a modulated input is impressed at input 75. Oscillator tube 34 is also coupled through coupling capacitor 47 to

power amplifier tube 35 and its associated circuit. The power amplifier tank circuit consists of inductance 64 tuned by the variable capacitor 52 which is in turn shunted by fixed capacitors such as 53, 54, 55, and 56. These fixed capacitors may be cut in or out of the circuit for tuning by means of switch 94. Inductance 65 is inductively coupled to inductance 64 and couples to the 115 volt power line through attenuator 90 and capacitors 57 and 58, at terminals 88 and 89, or these terminals 88 and 89 can be connected to a radio frequency transmission line 91, said line to run parallel and in close proximity to a power line 92 and ending in a terminating unit 93. This latter method of coupling is shown in Fig. 1A and description thereof. Voltage regulator tubes 36 are required for stable operation of tube 32, 33, and 34.

Rectifier tube 38 is a full wave rectifier which 20 with its associated power transformer 72 supplies high voltages to the plates and screen grids of the transmitter tubes. Filter chokes 92 and 93 in conjunction with filter capacitors 59, 60, and 61 produce a smooth direct current output from 25 the power supply.

The frequency modulated zone receiver is illustrated in Figs. 4 and 5, particular reference being made to Fig. 4, where the same is shown in block 30 diagram, consists of an antenna 95, a R. F. amplifier 96, a converter 97, an I. F. amplifier 98, a limiter 99, a discriminator 100, and an A. F. amplifier 101, which leads to the amplitude-modulated transmitter. Leading from the limiter 99, is a D. C. amplifier 102 operating relay 103, which 35 in turn controls said amplitude modulated transmitter when the central station transmitter is in operation.

The detailed circuit as shown in Fig. 5 is for 40 the most part a conventional superheterodyne receiver except for the addition of limiter tubes 109 and 110 and discriminator tubes 111 and 112 and consists of two radio frequency tube stages 104 and 105, a converter tube 106, followed by two 45 intermediate frequency tubes 107 and 108. The signal is then applied to the cascade limiter consisting of tubes 109 and 110 so that the amplitude of the applied signal is materially reduced thereby suppressing noise disturbances to a large degree. The FM signals are then applied to a 50 phase-shift type of discriminator, tubes 111 and 112 and associated circuit where the frequency deviations are converted into amplitude variations. The resulting audio frequency signal is then amplified by tube 113 and fed through transformer 228 where it then goes to the output receptacle 244. Receptacle 244 connects to the amplitude modulated zone transmitter. Gain control 215 regulates the volume of the signal to the desired amount. A conventional power supply and filter with tube 116 supplies plate and 55 heater current for this receiver.

As a result of the limiter action occurring in tube 109 a D.-C. voltage is developed across resistor 202. This negative voltage is applied to a 60 D.-C. amplifier comprising tubes 114 and 115. The output of tube 115 is connected to relay 240 which leads to output terminals 241. Contacts on relay 240 control the plate voltage supply of the A. M. transmitter. Relay 240 operates only 65 when sufficient negative voltage is obtained from resistor 202 and this occurs only when the carrier frequency of the FM central station transmitter is being received.

Fig. 6 is the block diagram of the amplitude 70 modulated zone transmitter operating on some

established frequency in the range limit of standard broadcast receivers employed, and usually at a predetermined frequency found to be signal free, and in this instance 590 kilocycles. In this instance, for example, master oscillator 250 is amplified by power amplifier 251 and the R. F. output is then fed to the antenna 247. The power amplifier 251 is modulated by audio amplifier 248 which can be operated by any type of signal source such as microphone 248 or connected to the output terminal 244 of the frequency modulated zone receiver described in Fig. 5.

In Fig. 7 is a detailed circuit of Fig. 6. Oscillator tube 252 is tuned by oscillator tank 253 and coupled to power amplifier tube 254 and its associated circuit through capacitor 255. The modulated output of this tube 254 is coupled through its tank inductance 256 to output coupling inductance 257. The modulating input 246 to the audio system is coupled through the speech input transformer 258 and the output of this transformer connects to audio driver tube 259. A class B driver transformer 260 couples tube 259 to the push-pull class B modulator tube 261 which in turn connects to the modulation transformer 262. This transformer 262 supplies class B modulation to the power amplifier tube 254.

A conventional power supply for the transmitter consists of plate transformer 263, rectifier tube 264, filter chokes 265 and 266 and filter capacitors 267 and 268. Heater current for all tubes is supplied by transformer 269. Switch 270 controls the input from the 115 volt line to the power supply while switch 280 controls the operation of the plate supply transformer. Terminals 272 permit the transmitter to be controlled from output terminals 241 controlled by relay 240 of Fig. 5, so that signals from the 100 kilocycle central station transmitter will be re-broadcast automatically.

In operation, this amplitude-modulated zone transmitter has its frequency determined by setting the master oscillator tuning condenser 273, the proper setting being determined from the calibration curve. With the R. F. output disconnected, the power amplifier coarse adjustment switch 274 is rotated until a dip is obtained on the plate milliammeter 281. The power amplifier fine adjustment tuning condenser 275 is then adjusted to give a minimum deflection on the plate milliammeter 281. The R. F. output 276 is plugged into a 115 volt source with the R. F. output attenuator 277 set approximately in half-way position. Then the coupling is varied between amplifier tank 256 and output coil 257 until a maximum desired deflection is obtained on the plate meter 281, or output terminals 276 may be coupled to a tuned transmission line as disclosed in Fig. 1A. The audio-frequency attenuator 279 is now adjusted so that the modulation indicator 278 flashes only on severe peaks, and should the indicator 278 remain lighted, there will be severe distortion.

Fig. 1A shows an alternate method of applying induction radio signaling to a power line circuit. Microphone 15 or dual turntable with amplifiers 14 is connected to a 100 kilocycle frequency modulated central station transmitter 13. The output from transmitter 13 is then fed into a tuned line 120 which extends for a distance of from 500 to 1000 feet substantially parallel and in close proximity to a conventional 2300 volt primary power circuit 122. Tuned line 120 is terminated at its extreme end by a suitable terminating unit 121 to avoid standing wave radiation, substan-

tially confining the signals to the power line and its immediate field.

The illustration indicates that the circuit 122 may run for a distance in underground conduit 123 before coming to the surface at zone 1 where the FM induction radio signals are picked up by receiving antenna 124 which connects to zone receiver 127 as previously described and illustrated in Figs. 4 and 5. Zone receiver 127 in turn 10 is connected to the A. M. transmitter 128 and with identical relay control circuit 129 as previously described in detail in reference to Fig. 5. The A. M. zone transmitter operating on 590 kilocycles is then fed into tuned line 130, said line 15 being terminated by a terminating unit 131 to eliminate standing waves in the same manner as described in reference to FM antenna 120. This line 130 is run parallel and preferably in close proximity to the 2300 volt power circuit for a distance of from 500 to 1000 feet thereby imposing the 590 kilocycle A. M. signal back into the local zone circuit and its secondary power circuits such as circuit 132 to which may be connected a conventional broadcast receiver 135. Any number of 20 similar receivers can be used to pick up the signal on this and other circuits in the zone. The broadcast receiver 135 picks up the signal from the power circuit inductively by antenna 136.

From the foregoing descriptions taken in connection with the drawings, it should be evident that an induction radio signaling apparatus is provided.

Inasmuch as the transmission of the amplitude-modulated transmitter must be of a type that transmits only to a restricted zone, it will 35 be noted that by the adjustment of the several elements thereof, and more particularly the attenuator 279, which not only acts as a radio frequency attenuator but also a line coupling device, 40 such result is attained, and that only receivers within the restricted zone will be affected thereby.

Also that it is specially useful in army camps, and similar places where broadcasting of a more 45 or less secret nature is desirable. Also that with this system receiver sets of conventional types can be utilized in the houses or homes within the selected area; and that with this system the signals are confined within such area for the system 50 permits establishment of a purely localized broadcasting service in the broadcast band with transmission of effective signals being confined substantially within limits of, as for instance, the camp area. This system thereby affords a 55 relative degree of security in such transmissions as compared with those of normal space-radio systems and permits, as before noted, of the use of conventional broadcasting receivers in all buildings within the entire camp area which may 60 extend many square miles.

It will also be understood that a frequency-modulated central station transmitter sends out the broadcasting signals from a central studio located for example, at an army camp, then 65 through the distributing network extending throughout the camp or other area. The induction radio field, extending laterally from these conductors reaches out for a distance of several hundred feet in actual use, dropping away so rapidly that at a distance of 300 to 400 feet, the signal ordinarily is below the noise level. Also the signal intensity of the induction field, as measured with a field strength meter located at 70 a given lateral distance from the conductors at 75 the edge of the selected area, may be regulated

to a desired field strength value, and which in this country would be specified by the Federal Communications Commission's regulations.

While certain specific illustrations of the invention are shown, it is to be understood that they are merely illustrative of the invention and that many other modifications may be employed without departing from the spirit of the invention as defined by the subjoined claims.

What I claim as new and desire to secure by Letters Patent of the United States is:

1. In a carrier wave communications system, means for generating a frequency-modulated carrier, means for coupling said frequency-modulated carrier to a distributing network, means for coupling said network to a receiver responsive to frequency modulation, an amplitude modulated transmitter, means for coupling said frequency modulated receiver output to an amplitude modulated transmitter operating on a frequency different than said first transmitter, means for coupling the output from the amplitude modulated transmitter back into said distributing network, a second receiver operating in the local zone area of the distributing network and tuned to the frequency of said amplitude modulated transmitter, and means for reproducing into sound the output of the second receiver.

2. In a restricted zone signaling system, means for generating frequency modulated radio frequency signals, means for coupling, superimposing, and adjusting the frequency modulated radio frequency signals to a predetermined level on an electric transmission line, means for coupling said transmission line to a receiver located at a remote point, coupling means for re-impressing the received intelligence of said radio frequency signals on a second transmitter, a second transmitter of the amplitude modulation type operating on a frequency different than said first transmitter, means for coupling, superimposing and adjusting to a predetermined level the second frequency on said electric transmission line, a receiver disposed within the restricted signaling zone established by the second transmitter and adjusted to said second frequency, and means connected to the output of said receiver for translating the intelligence of said second frequency.

3. In a restricted zone signaling system, means for generating frequency modulated radio frequency signals, means for coupling, superimposing, and adjusting the frequency modulated radio frequency signals to a predetermined level on an electric transmission line, means for coupling said transmission line to a receiver located at a remote point, coupling means for re-impressing the received intelligence of said radio frequency signals on a second amplitude modulated transmitter, said second amplitude modulated transmitter operating on a frequency different than said first transmitter, the frequency between said second transmitter and said first transmitter being such as to eliminate interaction therebetween, means for coupling, superimposing and adjusting to a predetermined level the second frequency on said electric transmission line, a receiver disposed within the restricted signaling zone established by the second transmitter and adjusted to said second frequency, and means connected to the output of said receiver for translating the intelligence of said second frequency.

4. In a restricted zone signaling system, means for generating frequency modulated radio frequency signals, means for coupling, superimposing, and adjusting the frequency modulated radio

frequency signals to a predetermined level on an electric transmission line, said radio frequency being of such a value as to pass through line transformers with minimum attenuation, means for coupling said transmission line to a receiver located at a remote point, coupling means for re-impressing the received intelligence of said radio frequency signals on a second amplitude-modulated transmitter, said second amplitude-modulated transmitter operating on a frequency different than said first transmitter, the frequency difference between said second transmitter and said first transmitter being such as to eliminate an interaction therebetween, means for coupling, superimposing and adjusting to a predetermined level the second frequency on said electric transmission line, a receiver disposed within the restricted signaling zone established by the second transmitter and adjusted to said second frequency, and means connected to the output of said receiver for translating the intelligence of said second frequency.

5. In a restricted zone signaling system, means for generating frequency modulated radio frequency signals, means for inductively coupling said frequency modulated radio frequency signals to an electrically conducting line of said system, a termination unit connected to said last means to restrict the formation of standing waves thereon, means for inductively coupling said electrically conducting line to a receiver, coupling means for re-impressing the received radio frequency signals on a second amplitude modulated transmitter, said second amplitude modulated transmitter operating on a frequency different than said first transmitter, means for inductively coupling the second frequency signals to an electrically conducting line of said system, a termination means connected to said last named means to restrict the formation of standing waves thereon, a receiver disposed within the restricted signaling zone established by said second transmitter and adjusted to said second frequency, and means connected to the output of said receiver for translating the intelligence of said second frequency.

6. In a restricted zone carrier wave signaling system having at least one electrically conducting line, a frequency-modulated transmitter for transmitting modulated radio frequency signals, means for coupling said modulated radio frequency signals to an electrically conducting line of said system, a plurality of frequency modulation receivers, means for coupling said electrically conducting line of said system to said plurality of receivers, a plurality of amplitude modulated transmitters, coupling means for re-impressing the received radio frequency signals on said plurality of amplitude modulated transmitters, one of said plurality of amplitude modulated transmitters being complementary to one of said plurality of receivers, each of said plurality of transmitters operating on a frequency different than said first frequency-modulated transmitter, and means for coupling each of said complementary transmitters to an electrically conducting line of said system.

7. In a centrally controlled carrier wave distribution system having at least one electrically conducting line, a central station frequency modulated transmitter, means for modulating said central frequency modulated station transmitter, a radio frequency attenuator and line coupling unit connected to the output of said transmitter, the output of said radio frequency

attenuator and line coupling unit being connected to said electrically conducting line, a secondary communications distributing system including a frequency modulated zone receiver and an amplitude modulated zone transmitter, means for automatically initiating operation of the amplitude modulated zone transmitter when the carrier from the frequency modulated zone receiver is impressed upon said amplitude modulated zone transmitter, and a zone radio frequency attenuator and line coupling unit connected to the output of said zone transmitter, the output of said zone radio frequency attenuator and line coupling unit being connected to said electrically conducting line to establish a localized amplitude modulated signaling zone.

8. In a centrally controlled carrier wave distribution system having at least one electrically conducting line, a frequency modulated central station transmitter, means for modulating said frequency modulated central station transmitter, a radio frequency attenuator and line coupling unit connected to the output of said transmitter, the output of said radio frequency attenuator and line coupling unit being connected to an electrically conducting line of said system, a secondary communications distributing system including a frequency modulated zone receiver and an amplitude modulated zone transmitter, means for automatically initiating operation of the amplitude modulated zone transmitter when the carrier from the frequency modulated zone receiver is impressed upon said zone amplitude modulated transmitter, and a zone radio frequency attenuator and line coupling unit connected to the output of said amplitude modulated zone transmitter, the output of said zone radio frequency attenuator and line coupling unit being connected to an electrically conducting line of said system.

9. In a restricted zone carrier wave signaling system having at least one electrically conducting line, a frequency modulated central station transmitter for transmitting modulated radio frequency signals, means for coupling said modulated radio frequency signals to an electrically conducting line of said system, a plurality of frequency modulated zone receivers, means for coupling said electrically conducting line of said system to said plurality of frequency modulated receivers, a plurality of amplitude modulated zone transmitters, coupling means for re-impressing the received radio frequency signals on said plurality of amplitude modulated zone transmitters, one of said plurality of amplitude modulated zone transmitters being complementary to one of said plurality of frequency modulated receivers, each of said amplitude modulated zone transmitters in adjacent zones operating on different frequencies, all of said zone amplitude modulated transmitters operating on a frequency different than said frequency modulated central station transmitter, and means for coupling each of said complementary amplitude modulated transmitters to an electrically conducting line of said system.

10. In a restricted zone carrier wave signaling system having at least one electrically conducting line, a frequency modulated central station transmitter for transmitting modulated radio frequency signals, means for inductively coupling said modulated radio frequency signals to an electrically conducting line of said system,

termination means connected to the coupling means to restrict the formation of standing waves on said coupling means, a plurality of frequency modulated zone receivers, means for coupling said electrically conducting line of said system to said plurality of frequency modulated receivers, a plurality of amplitude modulated zone transmitters, coupling means for re-impressing the received radio frequency signals on said plurality of amplitude modulated zone transmitters, one of said plurality of amplitude modulated zone transmitters being complementary to one of said plurality of amplitude modulated receivers, each of said amplitude modulated zone transmitters in adjacent zones operating on different frequencies, all of said amplitude modulated zone transmitters operating on a frequency different than said frequency modulated central station transmitter, means for inductively coupling each of said complementary amplitude modulated transmitters to an electrically conducting line of said system, and termination means connected to each of last said coupling means to restrict the formation of standing waves on each of last said coupling means.

11. In a centrally controlled carrier wave distribution system having at least one electrically conducting line, a frequency modulated central station transmitter, means for modulating said frequency modulated central station transmitter, a radio frequency attenuator and line coupling unit connected to the output of said transmitter, the output of said radio frequency attenuator and line coupling unit being connected to said electrically conducting line, a secondary communications distributing system including a frequency modulated zone receiver and an amplitude modulated zone transmitter, means for automatically initiating operation of the amplitude modulated zone transmitter when the carrier from the frequency modulated zone receiver is impressed upon said amplitude modulated zone transmitter, said automatic initiating means including a carrier-operated relay responsive to operation of said frequency modulation zone receiver, and a power supply relay responsive to operation of said carrier-operated relay to supply plate voltage for said amplitude modulated zone transmitter, and a zone radio frequency attenuator and line coupling unit connected to the output of said amplitude modulated zone transmitter, the output of said zone radio frequency attenuator and line coupling unit being connected to said electrically conducting line to establish a localized signaling zone.

12. In a communications system of the class described utilizing a distributing network, a frequency modulated master transmitter, means for modulating said master transmitter, a distributing network, means for coupling said master transmitter to said distributing network, a plurality of frequency modulated zone receivers, means for coupling said zone receivers to the distributing network, a plurality of amplitude modulated zone transmitters to operate on substantially identical frequencies, means for coupling each of said frequency modulated zone receivers to a complementary amplitude modulated zone transmitter, and means for coupling said zone transmitters to the distributing network.
